ABSTRACT OF THE DISCLOSURE

When drawing strip material from a coil on a pay-off device by drive means it is desirable that the end of the coil be drawn off of the pay-off device at a very low speed and as it is also desirable for the remainder of the coil to be drawn off of the pay-off device at as high a speed as possible, it is necessary to initiate deceleration of the drive means at a particular instant of time which will cause the drive means to be decelerated to zero just as the end of the coil is leaving the pay-off device. It is difficult for an operator to know at what moment to initiate deceleration of the drive means since the time at which initiation of the deceleration is started depends upon a number of features including the linear speed of withdrawal of the strip. The invention provides control means which automatically initiate deceleration of the drive means so that at the end of the deceleration period the end of the strip material is at a predetermined position relative to the pay-off device.

This invention relates to the control of strip material drawn from a coil on a pay-off device.

When strip material is drawn from a coil on a pay-off device by driving means, for example, a rolling mill, it is difficult for an operator to know at what moment to initiate deceleration of the driving means since the strip thickness and speed will vary from coil to coil.

In one aspect the invention provides apparatus for controlling strip material, comprising a strip pay-off device associated with driving means for drawing strip therefrom, comprising means for obtaining a continuous signal proportional to the size of the coil on the pay-off device, and means responsive to this signal for initiating deceleration of the drive means at a predetermined rate.

In another aspect the invention comprises apparatus for control of strip material, comprising a pay-off device associated with driving means for drawing material therefrom, means for obtaining a continuous measure of the radius of a coil on the pay-off device and means responsive to said latter means for initiating deceleration of the strip driving means at a predetermined rate, such that at the end of the deceleration period the end of the strip material has just left the pay-off device.

The invention further provides a method of controlling strip material drawn from a coil on a pay-off device which comprises obtaining a continuous measure of the size of the coil and using the measure to initiate deceleration of the strip driving means at a predetermined rate.

The radius of the coil can be measured by an arm and roller resting on the coil or can be calculated from a measure of the rotational speed of the pay-off device and the strip speed.

If the radius of the coil wound on the pay-off device of radius r_0 is r , then the annulus area of the strip is $\pi(r^2 - r_0^2)$.

If the length of the strip material wound on the pay-off

2

device is L and the thickness is h , then the annulus area is Lh .

$$\therefore Lh = \pi(r^2 - r_0^2)$$

$$\therefore r = \sqrt{r_0^2 + \frac{Lh}{\pi}} \quad (A)$$

If the linear strip speed is V and the deceleration rate is f , the deceleration time to zero strip speed is V/f at an average speed of $V/2$; thus the length of strip leaving the coil from start of deceleration to zero speed is $V^2/2f$.

If at the completion of deceleration the end of the strip material has just left the pay-off device the length Lx of coil on the reel at initiation of deceleration is $Lx = V^2/2f$.

Substituting this in Equation A, we get

$$rx = \sqrt{r_0^2 + \frac{V^2h}{2\pi f}} \quad (B)$$

where rx is the coil radius at which the deceleration should be initiated. If the strip speed V and the thickness h are known then rx can be calculated and deceleration arranged to be initiated automatically when the coil radius reaches rx .

One embodiment of apparatus for control of a strip pay-off device, in accordance with the invention, will now be described by way of example only, with reference to the accompanying diagrammatic drawing. A coil 12 having an inner radius r_0 and an outer radius r is mounted on a strip pay-off device 13. Strip from the pay-off device passes between the rolls 14 of a rolling mill driven by a motor M and onto a coiler 15. The strip is engaged by a billy roll 16 connected with a D.C. tachometer 17 which gives out a signal on line 18 proportional to the linear speed V of the strip. A small roller 20 carried on an arm 21 is urged by a spring 22 into continuous contact with the outer surface of the coil 12 the arm 21 is toothed and engages with a toothed wheel 23 which through arm 24, gears 25 and arm 26 operate a radius measuring potentiometer 27 which emits a signal on line 28 proportional to the radius r . The signal on line 28 is fed to a squaring circuit 30 which emits a signal proportional to r^2 on line 31 to a summing amplifier 32. The signal on line 18 is fed to a squaring circuit 33 which emits a signal on line 34 proportional to $-V^2$; this signal, together with a signal on line 35 representing the predetermined deceleration f and a signal on line 36 representing the strip thickness h are fed to a plurality of decade switches 37 from which is emitted on line 38 a signal proportional to $-V^2h/2\pi f$; the latter signal is also fed to the summing amplifier 32 which passes a signal on line 39 proportional to

$$r^2 - \frac{V^2h}{2\pi f}$$

to a level switch 40 also receiving a signal on line 41 proportional to r_0^2 the level switch 40 is arranged to emit a signal on line 42 when

$$r^2 - \frac{V^2h}{2\pi f} = r_0^2$$

signal on line 42 passes via a mill stop relay 43 to the motor M to initiate deceleration at the predetermined rate.

The coil radius r at any time is given by the relation $V/2\pi N$ where N is the rotational speed of the pay-off device, so that a measure of r may alternatively be obtained by measuring V and N and calculating r .

The value of h may alternatively be measured by a flying micrometer, an isotope gauge or calculated from the reduction in coil radius per revolution of the pay-off device or a relationship between rate of change of coil diameter or pay-off speed and strip speed. 5

We claim:

1. Apparatus for controlling strip material comprising, a pay-off device for supporting a coil of strip, drive means for drawing strip from a coil on said pay-off device, and 10 control means for controlling said drive means comprising, size measuring means for continuously deriving an electrical signal proportional to the size of the coil on the pay-off device, 15 speed measuring means for continuously deriving an electrical signal proportional to the linear speed of the strip material, and deceleration means responsive to these signals for initiating deceleration of said drive means at a predetermined rate and for a predetermined period so that at the end of the deceleration period the end of the strip material is at a predetermined position relative to the pay-off device. 20
2. In combination with a pay-off device for supporting a coil of metallic strip material, a rolling mill having a pair of rolls for drawing strip from the pay-off device and an electric motor for rotating said rolls, control means for controlling said motor comprising, 25 size measuring means for continuously deriving an electrical signal proportional to the radius of a coil on said pay-off device, speed measuring means for continuously deriving an electrical signal proportional to the linear speed of the strip material, and deceleration means responsive to these signals for initiating deceleration of said motor at a predetermined rate and for a predetermined period such that at the end of the deceleration period the end of the strip material has just left the pay-off device. 30
3. Apparatus for controlling strip material comprising, a pay-off device for supporting a coil of strip, drive means for drawing strip from a coil on said pay-off device and control means for controlling said drive means comprising, 35 size measuring means for continuously deriving an electrical signal proportional to the square of the outer radius of the coil on the pay-off device (r^2),

speed measuring means for continuously deriving an electrical signal proportional to the square of the linear speed of the strip (v^2), means for deriving an electrical signal proportional to a predetermined deceleration rate of the drive means (f),

means for deriving an electrical signal proportional to the thickness of the strip (h), means arranged to receive said signals and combine said signals to obtain a further signal proportional to

$$r^2 - \frac{v^2 h}{2\pi f}$$

means for deriving an electrical signal proportional to the square of the radius of the inner surface of the coil (r_0^2) and means arranged to receive said further signal and said signal proportional to r_0^2 and to compare said signals to initiate deceleration of said drive means when

$$r^2 - \frac{v^2 h}{2\pi f} = r_0^2$$

whereby

the drive means is decelerated at the predetermined rate to standstill as the end of the strip material has just left the pay-off device.

4. Apparatus for controlling strip material as claimed in claim 1 in which the size measuring means includes an arm arranged to remain in contact with the outer surface of the coil, means for measuring the position of the arm and means for producing an electrical signal proportional to the measure of the position of the arm.
